SWITCH PLUG CONNECTER

Pearley B. Boone, San Francisco, Calif.

Application May 15, 1934, Serial No. 725,714

12 Claims. (Cl. 200—51)

This invention relates to electrical connectors and has for its objects an improved electrical connector of the switch plug type that is composed of extremely few parts and that is easily and quickly assembled and disassembled and in which the switch member coats with the plug parts to retain the plug in assembled relation. Other objects and advantages will appear in the following specification and drawing.

10. In the drawing, Fig. 1 is a broadside view of my connector assembled.

Fig. 2 is an edge view of the connector of Fig. 1.

15. Fig. 3 is a sectional view of Fig. 2 taken along the line 3—3 thereof.

Fig. 4 is a view of the connector of Fig. 3 with the parts in disassembled relation and with the terminal elements removed, one of the parts being in section.

20. Fig. 5 is an assembled end view of one of the parts of Fig. 4 as seen from the line 5—5 of Fig. 4, the terminal elements being in place.

Fig. 6 is an end view of one of the parts of Fig. 4 as seen from the line 6—6 of Fig. 4 with the 25 terminal elements in place.

Fig. 7 is a perspective view of the switch member, or the element shown in Fig. 4 between the two outer members of the plug.

Fig. 8 is a perspective view of one of the electrical conductor terminals showing the wire connected thereto.

Fig. 9 is a perspective view of one of the terminals of the plug that is adapted to engage one of the posts of an electrical appliance.

35. Briefly described my invention, as shown in the drawing, comprises an elongated body divided transversely of its longitudinal axis into two parts, one of which parts is split longitudinally, and is internally recessed to carry the electrical conductor terminals and the other part is in one piece longitudinally apertured to carry the connector elements or terminals adapted to engage the posts of an electrical appliance. The two parts of the body, one being split and the other a single piece as above described, are connected by a sliding switch block adapted to connect and to disconnect the conductor terminals and the terminals engaging the appliance posts, and which block also serves to assist in connecting the two parts of the body against separation.

In detail my switch plug comprises an elongated body divided transversely of its longitudinal axis into an outer plug member 1 formed in one piece and an inner plug member that is 55 split longitudinally of the body axis into simi-

larly shaped halves 2, 3. The outer plug member is formed with side portions 4 extended from two opposite sides of the plug member longitudinally of the body. Each of the halves 2, 3, of the inner plug member is formed with an extension 5 adapted to fit between the side portions 4 of the plug body and are spaced apart to permit a switch block 6 to pass transversely of the longitudinal axis of the body between the extensions 5 and through square openings 6' extending through the portions 4 of the plug body, said switch block being of oblong shape and substantially square in cross section.

Adjacent the side edge of extensions 5 the main body of the halves 2, 3 respectively projects laterally outwardly forming a square shoulder and an upstanding flange 7 is formed on each shoulder adjacent the line of division between the halves, which flanges are adapted to fit within grooves 8 formed on the outer ends of the extensions 4 of the plug body.

The inner opposed sides of the extensions 4 are each provided with a guide member 9 extending transversely of the axis of the body, which guides are adapted to slidably engage in grooves 10 on opposite sides of the switch block 5, said grooves terminating adjacent one end of the switch block at a point spaced slightly from the end of the block, thus forming stops 11 at the blind end of the grooves adapted to engage the ends of the guides 9 to prevent the switch block from being forced completely through the body from one side and out the other side.

From the foregoing description it is seen that when the flanges 7 are engaged in grooves 8 and the grooves in the sliding block engage the guides 9, the parts 2, 3 are prevented from being withdrawn from the outer plug member and are also retained against separation of the parts 2, 3 of the inner plug member adjacent the transverse division between the inner and outer plug members.

The parts 2, 3 respectively are substantially triangular in shape as viewed from the side, best seen in Fig. 4, with the apex of the triangular portion extended in a tubular neck 12 and with the base of the triangle extending along a line x drawn through flanges 7. The neck 12 terminates in laterally extending arms 8' adapted to be grasped by the fingers of the hand of the operator for manipulating the plug in connecting and disconnecting the plug from an appliance. The extreme longitudinal end of the neck 12 has an outwardly projecting hub 13 in concentric alignment with the neck, which hub is provided

with an annular groove around its outer side for receiving a ring of rubber or spring ring 14' that secures the outer ends of parts 2, 3 against separation.

5 Adjacent the base of the triangular portion of the inner plug members, as indicated by line x, the parts 2, 3 are oppositely recessed on adjacent sides at 15, 15'. These recesses are spaced from each other by an inverted V-shaped rib 14 similarly formed in each half, said recesses respectively opening into the transverse passage formed between extensions 5 for the passage of the switch block 6, there being a slight shoulder 17 along the side of the recesses adjacent the openings into the switch block passage for a purpose to be later described.

The apex of the rib 14 is positioned adjacent the switch block passage, and the arms of the ribs in each of the halves 2, 3, are transversely 20 grooved on their adjacent sides at 20, which grooves provide for communicating openings between recesses 15, 15' and a recess 21 positioned between the arms of the rib, the recess 21 communicating in turn with the inner end of bore 22 25 in the neck 12, said bore extending through the hub 13.

The outer plug member 1 is provided with a pair of spaced passages 25 extending longitudinally through the plug member, which passages 30 communicate at their inner ends with the switch block passage. A central rib 26 spaces the passages from each other. These passages 25 are substantially rectangular in cross section, and the opposite sides of the walls of the passage are 35 inclined outwardly from point 27 to the switch block passage, as at 27' and the opposite lateral sides of rib 26 are inclined toward each other from adjacent point 27 to the switch block passage.

40 A terminal element 25' is fitted within each of the passages 25, said elements each comprising an elongated strip of spring sheet metal bent inwardly transversely of its length at two spaced points 28 and then outwardly at 28' to form two 45 substantially parallel legs 30 extending outwardly from convergently extending portions 29 with a flat end 32 connecting across the ends of the inclined portions. The inclined portions 29 angularly correspond to the inclined sides 28' of 50 passages 25 and one edge of the inclined portions 29 is slanted to fit against the inclined sides of the end of rib 25. This formation of the terminals 25' insures proper positioning of the terminals within the passages 25 respectively and 55 also provides for seating the terminals with the outer surfaces of their ends 32 substantially flush with the switch block passage that extends thereacross.

The flattened end 32 of each of the terminals 60 25' is provided with spaced slots 33 from one edge, thus providing a tongue 34 therebetween, which tongue is bent outwardly and then back again adjacent its free end, giving the tongue a V-shaped outer end that projects into the switch 65 block passage. The tongues of the terminals 25' extend oppositely longitudinally of the switch block passage when the terminals are in position, as best indicated in Fig. 3.

Referring again to parts 2, 3. Within the recesses 14, 15 I provide conductor terminals 35 of similar shape. These terminals are small strips of spring metal formed in a V-shape providing legs 36, 37. The leg 36 of each terminal is adapted to lie against the outer side respectively 75 of the legs of the V-shaped rib 14 with the apex

of the terminals adjacent the apex of the rib, but spaced apart by the rib.

The leg 37 of the terminals 35 lies substantially flush with the switch block passage and each is provided with a tongue 38 similar to tongues 34 of terminals 25', the tongues 38 being disposed directly opposite the tongues 34 respectively and projecting into the switch block passage in the same manner as said tongues 34. The other leg 36 of each terminal 35 is provided with an opening 39 through which one of the ends 40 of one of the conductor wires in the electrical cord 41 extends, the free outer edge of leg 36 being slotted at 42 in one or more places to one side of opening 39 so that the conductor end 40 may be wrapped 15 around the outer side edge of the leg 35 and then through slot 42, thus providing for a portion of the conductor extending between the outer surface of leg 35 and the outer surface of rib 14. The angular relation between the legs 36, 37 is 20 such that the legs must be compressed toward each other slightly in order to fit the terminal 35 in the recess 15 or 15', thus the end of the conductor between leg 36 and rib 14 is resiliently secured therebetween and cannot be withdrawn 25 by any pull on cord 41. The legs of the terminal 35 are retained in compressed position in the recess by reason of the fact that the side edges of leg 37 engages under shoulder 17 formed along the side of the recess. It may be noted that the 30 side edge of leg 36 of the terminal may be cut away, as at 43, if desired, to receive the conductor end 41 when the conductor is connected to the terminal as above described.

From the foregoing description, it will be seen 35 that with the plug assembled, with the exception of the switch block, the passage for the switch block is free to recess the block from either end thereof, and when the switch block is in position, the outer and inner plug members will be securely 40 locked together by the switch block.

The switch block, as already noted, is of oblong formation and substantially square in cross section with grooves 10 on two opposite sides adapted to slidably fit guides 9 on the extensions 5 of the 45 inner plug member.

The switch block is provided with two conductor plugs 45 extending transversely through the block at points spaced from each other the distance between the tongues 38 of the terminal elements 35, 50 which distance is, of course, the same as the distance between tongues 34 of terminals 25'. The opposite sides of the switch block are grooved transversely thereacross by V-shaped grooves 46 that cut across the opposite ends of each of the 55 conductor plugs, which grooves are adapted to recess the V-shaped ends of tongues 34, 38 of the terminal elements 35, 25' when the block is inserted into the switch block passage, thus making a connection between the terminals. Along 60 side these grooves 46 toward one end of the switch block are second V-shaped grooves 47 parallel to grooves 46. These grooves receive the tongues 34, 38 to retain the switch block in the "off" position with the terminals disconnected 65 when the block is moved longitudinally in the direction of the grooves 47. The stops 11, or blind end of slots 10 provide for limiting the movement of the switch block when it is in the "on" position and to limit the movement of the block 70 when it is in the "off" position and to also prevent withdrawal of the switch block after it has been inserted in the plug body, I provide a U-shaped spring clip 43 adapted to extend around the end 75 of the block at the free ends of grooves 10 and 75.

to lie in the groove, the free ends of the clip being inserted in recesses 49 in the bottoms of the grooves 10. This clip is easily removed by springing the arms apart if desired to remove the 5 switch block and disassemble the plug.

By the foregoing construction, the tongues on the terminals that engage the grooves in the switch block positively force the switch block to assume the "on" or "off" positions respectively, 10 and also it is to be noted that this switch provides for simultaneously breaking connections between terminals 38 and 34.

In order to prevent any relative movement between parts 1 and 2 in the plane of the division 15 between them, I provide posts 49 on opposite sides of bore 22 spaced points in the extensions 8' and a third post 49' adjacent the apex of rib 15, which posts extend into recesses in the opposed parts 2, 3.

20 To further stabilize the inner and outer plug members when in assembled position, the outer ends of extensions 5 overlap the opposite sides of the outer plug member a short distance at 50, best seen in Fig. 2 in dotted line, said ends 50 seating in a rabbeted edge of the outer plug member. Thus the inner and outer plug members are prevented from "breaking" angularly along the line of division between said members to cause 25 frictional resistance to free sliding of the switch 30 block.

Having described my invention, I claim:

1. An electrical plug connector comprising a body formed of two separate plug members each provided with a pair of spaced contact terminals 35 therein, a switch device movably mounted within the connector arranged and adapted to connect and to disconnect the pairs of terminals upon movement thereof, said plug members and switch device being formed and adapted to coact for 40 retaining the plug members connected together.

2. An electrical plug connector comprising an elongated body divided transversely of the longitudinal axis of the body into two separate plug members, a switch device movably mounted in the 45 body adjacent the line of division thereof, means on each of said plug members arranged and adapted to engage the switch device against separation of the plug members and a contact terminal positioned within each plug member adapted to 50 be connected and to be disconnected by the switch upon movement of said switch.

3. An electrical plug connector comprising a body formed of two separate plug members each provided with a pair of spaced contact terminals 55 therein, an elongated switch device of insulating material provided with a pair of spaced conductors extending transversely thereacross, said switch device being slidably mounted within the body of the connector between said pairs of contact terminals for longitudinal movement, the pairs of terminals being arranged and adapted to be simultaneously connected by the conductors of the switch device upon longitudinal movement of the switch device in one direction and to simultaneously disconnect the terminals upon movement of the switch device in the opposite direction, and means including said switch device for securing the plug members together.

4. An electrical plug connector comprising a 70 body formed of two separable plug members each provided with a pair of spaced contact terminals therein, one of said plug members being split perpendicularly to the line of division between the plug members for separation to expose the contact terminals therein for removal, a pair of elec-

trical conductor wires connected respectively to the terminals in the split plug member, a switch device movably mounted within the connector arranged and adapted to connect the pairs of terminals, said switch device and plug members being formed to engage each other against separation when the switch device is in position within the connector.

5. An electrical plug connector comprising a body formed of two separable plug members each 10 provided with spaced substantially parallel extensions projecting from two of their opposite sides respectively, the two extensions on one of said plug members adapted to fit between the two 15 extensions of the other plug member disposed in a plane perpendicular to the plane in which the said other extensions are positioned, the two extensions on one of said plug members being provided respectively with aligned openings therethrough and an elongated switch member 20 slidably mounted in said openings and between the extensions of the other plug member, means on the extensions of the other plug member slidably engaging opposite sides of said switch member and spaced conductors on the switch member 25 extending thereacross from one side to the other in the direction of the longitudinal axis of the plug, a pair of spaced contact terminals in each of said separable plug members arranged and adapted to be connected through said spaced 30 conductors upon longitudinal movement of said switch device, electrical conductor wires connected with the pair of contact terminals in one plug member and the other pair of contact terminals being adapted to connect to an electrical appli- 35

6. A plug connector comprising a body provided with a pair of outwardly opening recesses in one end thereof, a pair of contact terminals in said recesses, each of which is adapted to receive the 40 prongs of an electrical device through the openings to the recesses, a pair of electrical terminals in the opposite end of the body adapted to be connected to the conductor wires of an electrical circuit and a switch member movably mounted 45 between the pairs of terminals in opposite ends of the body arranged and adapted to simultaneously connect and to disconnect the respective pairs of terminals upon movement of the switch member in opposite directions, said body being divided 50 into two separate portions, one of which portions carries said pair of contact terminals and the other portion carrying the terminals adapted to receive the prongs of an electrical device, and the switch member being formed and adapted 55 to coact with the two separate portions of the body for securing them together against separation.

7. A screwless electrical conductor plug comprising a body divided into two halves each having an electrical contact terminal therein and a switch member movably mounted within the body arranged and adapted to connect and disconnect the terminals upon movement thereof and to secure the two halves together against separation.

8. In a plug connector comprising a body having openings in one end for admitting the conductor terminals of an electrical appliance to within the body, screwless conductor members 70 removably fitted within the body adjacent said openings for engagement by such conductor terminals, conductor wires extending into said body, and means for connecting the conductor wires to said conductor members, said conductor members each comprising a single elongated strip of re- 75

silient sheet metal bent to provide a pair of opposed legs with a section of said strip extending between the legs at an end thereof in a plane perpendicular to the legs, said section connecting and spacing said legs whereby the legs are adapted to extend on opposite sides of the aforesaid conductor terminals when the latter are admitted to within the body.

9. In a construction as defined in claim 8, said means for connecting the conductor wires and 10 conductor members comprising a switch member slidably supported on the respective sections connecting the legs of the conductor members.

10. A plug connector for electrical appliances 15 comprising a body, electrical conductor members fitted within said body, said body being formed with openings in a side arranged and adapted for admitting conductor terminals of an electrical appliance to within the body for engagement with 20 said conductor members, a generally T-shaped handle member separable from the body projecting from the side of the body opposite said openings disposed with its arms remote from the body, said handle member being formed and a 25 bore extending longitudinally through the leg adapted to pass electrical conductor wires therethrough for connecting with the conductor members, means rigidly connecting said handle member with the body arranged and adapted to pre-

vent lateral, longitudinal, and rotative movement of the handle member relative to the body and the end of the handle adjacent the body being enlarged to substantially the width and thickness of the end of the body adjacent thereto.

11. A plug connector for electrical appliances comprising a one-piece integrally formed body provided with a pair of through passages therein opening outwardly at opposite sides of the body, a pair of conductor members fitted within 10 said passages, a rigid generally T-shaped handle member provided with an enlarged base portion formed integrally therewith adapted to fit over the outer side of the body at one of the open ends of said passages and over said passages, the 15 leg of said T-shaped handle member projecting outwardly from said base portion with the arm of the T at the outer end of the leg remote from the body, said handle member being formed with a bore adapted for passing the ends of a pair of 20 conductor wires therethrough, means for rigidly connecting said handle member and body together against lateral and longitudinal movement of the handle member and body relatively.

12. In a construction as defined in claim 11, 25 means on said base portion adapted to space the ends of conductor wires passed through the bore.

PEARLEY B. BOONE.
